UNITED STATES PATENT OFFICE.

NORMAN F. OVERTURE, OF CLEVELAND, OHIO.

PROPELLER FOR AIRPLANES AND THE LIKE.

1,407,080.

Specification of Letters Patent. Patented Feb. 21, 1922.

Application filed February 7, 1921. Serial No. 443,030.

To all whom it may concern:

Be it known that I, NORMAN F. OVERTURE, a citizen of the United States, residing at Cleveland, in the county of Cuyahoga and 5 State of Ohio, have invented a certain new and useful Improvement in Propellers for Airplanes and the like, of which the following is a full, clear, and exact description, reference being had to the accompanying drawings.

This invention relates to propellers such as are employed with airplanes for the purpose of driving the same or with fans for moving air or other fluids. It is the general 15 object of the invention to provide a propeller of this kind wherein the pitch of the blades may be conveniently altered and reversed and one wherein such alteration and reversal may be accomplished without reversing the direction of rotation of the shaft. Further and more limited objects of the invention will appear hereinafter and will be realized in and through the construction and arrangement of parts illustrated in the 20 drawings forming a part hereof, wherein Fig. 1 represents a side elevation of a propeller of the character before set forth, together with its mounting and the means for driving, reversing and varying the pitch of 25 the blades thereof; Fig. 2 a detail in sectional elevation through the drive shaft and propeller, one of the bearings being omitted; Fig. 3 a detail in plan of the propeller and hub; Fig. 4 a detail in perspective of the 30 means for supporting one of the blades; Fig. 5 a detail in elevation of the hub and propeller blades taken at right angles to Fig. 3; Fig. 6 a detail in section corresponding to the line 6—6 of Fig. 3; and Fig. 7 a 35 similar view corresponding to the line 7—7 of Fig. 5.

Describing the various parts by reference characters, 1 denotes a pair of standards each having at its upper end a journal 2, the 45 said journals supporting a hollow shaft 3 through bearings 4. Uniting said standards and projecting horizontally therefrom is a frame member 5, also having a leg or standard 6. For convenience of description, the 50 end of the shaft 3 which carries the hub will be referred to as the "front" and the opposite end as the "rear," but without any intention of limiting my invention to such particular location.

55 The hub referred to is indicated at 7 and is keyed or otherwise suitably secured to

the shaft 3, as indicated at 8. This hub is adapted to support any desired number of propeller blades. In the drawing, two such blades are shown, indicated at 9 and each 60 supported upon the hub by means of a post 10 threaded or otherwise rotatably mounted within and secured to the hub. As shown, each post is longitudinally slotted for the reception of its blade and is secured thereto 65 by rivets 11. The inner end of each propeller blade is mounted in the slotted ends 12^a of a base 12 through which the body of the post 10 extends. Each of these bases is provided with a slot 13 extending longitudinally thereof and transversely of the 70 hollow shaft 3.

Slidably mounted in the shaft 3 is a rod 14. Extending through the said rod is a pin 15 having its opposite ends located within 75 the slots 13 of the two base members 12 and extending through opposed slots 16 in the hub 7. The inner end of each propeller blade 9 is slotted, as indicated at 9^a, to accommodate the adjacent end of the pin 15. The 80 pin is retained within the rod 14 in any convenient manner, as by an axially extending set screw 17.

For the purpose of operating the said rod and thereby causing the pin 15 to rotate 85 the propeller blades about their supports on the hub, I provide a ring 18 which surrounds an inner collar 19 having a pin 20 extending through opposed slots 21 in the shaft 3 and through a bore in the said rod. The 90 ring 18 is provided with a pair of outwardly extending pins 22 which engage the slots 23^a in a yoke 23 carried by a lever 24 pivoted to the horizontal frame member 6. The end of the lever opposite the pins 22 is connected 95 to one end of a link 25, the opposite end of which is connected to a lever 26 having a spring pressed locking detent 27 adapted to engage the notches 28^a of a rack segment 29.

For the purpose of driving the shaft 3, 100 the latter is shown as provided with a pulley 30, there being a belt 31 and a pulley 32 on the shaft 33 of a motor 34 by means of which said propeller shaft may be driven.

With the parts constructed and arranged 105 as described, power will be transmitted from the motor 34 to the shaft 3, thereby to rotate the same and the propeller blades. The parts are so arranged that, by moving the lever 26, the rod 14 will be correspondingly moved 110 within the shaft 3, thereby to rotate the propeller blades about their axes and upon their

- bases 12 and thus to vary and reverse the pitch of said blades. When the lever 26 is locked in a vertical position to the gear segment, the propeller blades will be locked in 5 the neutral position shown in Fig. 3. If the lever be moved to the left of the central notch on the rack segment, the blades will be given a pitch in one direction which will increase with the distance the lever is moved 10 from such central notch. If the lever be moved in the opposite direction from such central notch, the pitch will be reversed and the amount of the pitch in this direction will increase with the distance of the lever 15 from such notch. Furthermore, it will be apparent that this reversal and variation in pitch may be accomplished without reversing the shaft 3, but by merely moving the rod 14 within the said shaft.
- 20 By means of my invention, it will be apparent that the pitch of the propeller may be conveniently adjusted to accommodate various conditions. In the case of an airplane, when at a high altitude, the blades may be 25 set to a pitch as high as 45° (with the parts constructed as shown herein) thereby insuring efficient operation of the propeller at such altitudes.

- Having thus described my invention, what 30 I claim is:
1. The combination of a hollow shaft, a hub on said shaft and having longitudinal slots extending in opposite directions from the central portion thereof, blades rotatably 35 mounted upon and extending from said hub, a rod slidably mounted in said shaft, pins carried by said rod and mounted in said slots, an operative connection between the

outer end of each pin and a blade for rotating the latter about its axis, the said shaft having a slot therein, a collar slidably mounted on said shaft and connected with said rod through said slot, a ring rotatably mounted on said collar, means connected with said ring for moving the said collar and the said rod, and means for driving the said shaft.

2. The combination of a hollow shaft, a hub mounted on said shaft and having slots extending from the central portion thereof, blades rotatably mounted on said hub and each having a base extending across the outer end of a slot, a rod slidably mounted in said shaft, pins projecting from said rod and through the said slots and into the slots in 55 the bases of said blades, respectively, means for driving said shaft, means for moving the said rod longitudinally of said shaft, and means for supporting the said rod and thereby the said blades in various adjusted positions. 60

3. The combination of a hollow shaft having a hub, blades rotatably mounted on said hub and projecting therefrom, a rod slidably mounted in said shaft, means for driving 65 said shaft, means for reciprocating the said rod within the said shaft, means connected with the said rod for locking the same in any adjusted position with reference to said shaft, and connections between said rod and 70 said blades for rocking the same about their supports upon the said hub.

In testimony whereof, I hereunto affix my signature.

NORMAN F. OVERTURF.
